(57) **CLAIM**

The ornamental design for a laptop computer table, as shown and described.

DESCRIPTION

FIG. 1 is a front elevational view of a laptop computer table;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front isometric view thereof;

FIG. 8 is a rear isometric view thereof; and,

FIG. 9 is a front isometric view thereof, showing a laptop computer resting upon the laptop computer table.

The broken lines are for environmental purposes only and form no part of the claimed design.
